(57) **CLAIM**

The ornamental design for decorative stud holder, as shown and described.

DESCRIPTION

FIG. 1 is a top plan view of a decorative stud holder showing my new design;

FIG. 2 is a bottom plan view;

FIG. 3 is a right side elevational view, the left side elevational view being a mirror image;

FIG. 4 is a front elevational view;

FIG. 5 is a rear elevational view; and,

FIG. 6 is a top perspective view.

It being understood that the broken lines are for illustrative purposes only and form no part of the claimed design.
